(57) **CLAIM**

The ornamental design for an electronic computer with an at least partially transparent input device, as shown and described.

DESCRIPTION

FIG. 1 is a top perspective view showing of a first embodiment of our new design for an electronic computer with an at least partially transparent input device;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is a top perspective view showing a second embodiment of a design for an electronic computer with an at least partially transparent input device;

FIG. 9 is a front view thereof;

FIG. 10 is a back view thereof;

FIG. 11 is a side view thereof;

FIG. 12 is another side view thereof;

FIG. 13 is a top view thereof;

FIG. 14 is a bottom view thereof;

FIG. 15 is a top perspective view showing a third embodiment of a design for an electronic computer with an at least partially transparent input device;

FIG. 16 is a front view thereof;

FIG. 17 is a back view thereof;

FIG. 18 is a side view thereof;

FIG. 19 is another side view thereof;

FIG. 20 is a top view thereof; and,

FIG. 21 is a bottom view thereof.

The broken lines in the preceding FIGURES illustrate portions of the electronic computer and form no part of the claimed design.
